CLAIM

The ornamental design for a TV receiver, as shown and described.

DESCRIPTION

FIG. 1 is a front, right side, perspective view of a TV receiver showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion of the TV receiver shown in the area designated as 9 in FIG. 6;

FIG. 10 is a front, right side, perspective view of the TV receiver of FIG. 1, shown in an alternate configuration of use;

FIG. 11 is a rear perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof; and,

FIG. 17 is a bottom view.
